UNITED STATES PATENT OFFICE.

ALEXANDER F. JENKINS, OF BOONE, MARYLAND.

ACETYLENE GENERATOR.

Application filed March 15, 1922. Serial No. 543,820.

The invention relates to improvements in acetylene generators tending to efficiency, convenience and economy of operation and construction and to constructural features which contribute not only to these ends but to convenience in packing and protection of the apparatus during transportation whether packed or uncovered.

The use in apparatus of this nature of a 10 shut-off valve closing the gas delivery passage when the apparatus is not in use and a needle valve for adjusting the flow of gas to the burner, has been universal. In the present instance the applicant has combined 15 the needle valve with the shut-off valve and has provided the needle valve with a clean-out pin which projects through the burner aperture, moving back and forth therein as the size of the opening is adjusted or the 20 needle is moved back and forth in closing and opening the valve.

Also for convenience in taking down and assembling, the reflector which is centrally apertured to admit the burner has a collar 25 with a flange, which latter is riveted to the reflector surrounding the aperture. The burner as shown is shouldered providing a projecting portion which enters the collar.

Another feature of interest is the construction of the carbide holder or pocket with a bottom composed of a single piece of sheet metal enclosing a cover strap at the bottom which serves as a handle to be grasped by the operator in emptying the pocket of 30 burned carbide and other features as the holder is provided with a base or supporting ring which is attached to the bottom by ears which are cut from the bottom and bent 35 into contact with the ring and riveted or the like, making the bottom of a single piece 40 of sheet metal, which lends to convenience and economy of construction as well as to lightness and durability.

The apparatus as disclosed includes a 45 drum with a vent pipe and a delivery pipe. The pipes are spaced apart and extend upward to the top of the tank, both pipes are secured at their upper extremities to a cross-bar which may serve either as a handle for 50 the entire apparatus or as a handle for the drum and pocket.

The vent pipe also acts as a casing or housing for a fastening device which serves to hold the pocket in the drum, the same being 55 in the form of a rod which extends downward through the pipe having a hook at the

bottom and a swinging arm at the top, by means of the arm the rod is rotated throwing the hook at the bottom into and out of locking position, the locking position being 60 when the hook projects under the pocket and the cross-bar is preferably diagonal as to the tank holding the drum against rotary and lateral movement.

The tank is also provided with locking 65 means for the drum to prevent it from being lifted from the tank, making it possible to utilize the cross-bar at the top either as a handle for the drum and pocket or as a handle for the entire apparatus as aforesaid. 70

Another feature of the invention consists in the arrangement of the burner and reflector at an acute angle to the delivery pipe which latter is swiveled, making it possible to swing the reflector downward into position 75 with its flat circular edge or rim in close contact with the side of the tank. This gives economy of space in packing and also most efficient protection of the reflector and the burner.

In the accompanying drawing I have illustrated an apparatus embodying the improvements of my invention in the preferred form in which drawings:

Figure 1 is a vertical central section of 85 the entire apparatus;

Figure 2 is an elevation of the burner and swivelled delivery pipe separated from the apparatus;

Figure 3 is an elevation or external view 90 of the apparatus with the reflector folded down against the side of the tank as aforesaid;

Figure 4 is a top plan view of the pocket;

Figure 5 is a top plan view of the apparatus assembled;

Figure 6 is a section on the axis of the burner showing the burner and a portion of the reflector assembled;

Figure 7 is a vertical central section showing 100 the bottom of the pocket, the remainder of the pocket being broken away; and

Figure 8 is a bottom plan view of the pocket.

Referring to the drawings by numerals, 105 the apparatus comprises a tank 1, which in the form shown is open at the top at 2. In the tank is a drum or bell 3 closed at the top at 4 and open at the bottom, the bottom edge or rim 5 in the present instance resting on the bottom of the tank. Normally the drum or bell 3 is completely submerged

in the water in the tank within the drum or bell or otherwise suitably located. If the generator should be of a different type, it is perfectly feasible to vary the structure and mode of operation and still embody therein various features of the invention.

Within the drum is a carbide pocket 6 embodying several novel details but bearing a general resemblance to that disclosed and 10 claimed in my previous Patent No. 1,292,327.

Extending upward from the drum is a delivery pipe 9 and a vent pipe 10. These are both secured to a horizontal cross-bar 11 which as shown extends diagonally across 15 the tank and may serve as a handle either for lifting the entire apparatus, for lifting the drum alone or for lifting the drum with the carbide pocket or holder 6 depending on the arrangement of the locking devices to be described. The delivery pipe extends upward from the cross-bar 11 through which it passes and to which it is secured. A coupling 14 serves to attach to the delivery pipe 9 the upright extension or external portion 20 15 thereof, which as shown is packed with filtering material of a fibrous or any preferred nature 16 and is provided at its upper end with an elbow 17 to which is attached a swivel connection 18 carrying a swinging 25 feed pipe 19 swinging in a vertical plane parallel to the portion 15 and forming an extension of the delivery pipe which carries 30 at its upper extremity the lighting burner 20 and reflector 21. The burner includes a 35 burner proper or casting 22 and burner tip 23, the burner casting being threaded on to the end of the swinging feed pipe 19, the threaded connection being indicated by reference character 24.

More specifically the carbide holder 6 consists of vertical radiating plates 25 supporting perforated pockets 26 preferably overlapping in a vertical plane and helically arranged as in my previous patent referred to. 45 The holder is provided with a handle 27 in the form of a metal loop or band at the top. The bottom of the pocket 28 is of a single piece of sheet metal, double slotted centrally to form a band or strap 29 which is bent 50 downward to form a bottom handle, see Figures 7 and 8, the pocket or holder is also provided with a supporting ring 30 which is secured to the conical plate 28 by depending ears 31 cut from the bottom plate, bent downward and riveted at 32 to the supporting ring. This provides suitable passages 33 for the water through the bottom of the holder and contributes not only to economy 55 of production but to lightness, simplicity and durability as the method of construction serves to reduce the number of joints in the structure which might be subject to failure.

The pocket is when the apparatus is assembled for operation, placed in the drum 4 as 60 shown.

The delivery pipe 9 extends upward from the top of the drum being rigidly secured to the top of the drum by screw collars 35 and 36 inside and outside the top of the drum or in any other suitable manner. The 70 pipe 9 extends through the cross-bar 11 at its upper end, being held in position by a screw collar 13 beneath the bar which cooperates with the coupling 14 above the bar which coupling 14 serves as a means for connecting the outside pipe or delivery extension 15 as aforesaid. The vent pipe 10 as shown extends upward vertically along the side of the drum, being secured thereto at the top and bottom by any convenient means 80 as straps 37 and 38 and it may be spaced from the drum by blocks 39 and 40. The vent pipe as shown is open at the bottom and is connected to the bottom of the drum by a horizontal aperture 41 which extends through the block 40 through the side of the pipe and through the wall of the drum and at the top of the pipe 10 there is a vent-opening 41' just under the fitting 42 at the right, also the bearing of the shaft 45 where it extends 85 through the bar 11 and the fitting 42 not being packed provides for the gradual escape of gas. The vent pipe 10 as shown extends to the cross-bar 11 secured thereto in any suitable manner. This connection may be 90 made in any suitable manner as by means of a sitting 42 riveted to the bar and receiving the end of the vent pipe.

In the form of the invention shown the vent pipe 10 serves as a bearing or housing 100 for the lock shaft 45 which extends vertically the entire length of the vent pipe projecting from both ends. At the upper end it passes through the cross-bar 11 and has secured to its upper end above the cross-bar 105 an operating arm or lever 46 by which it may be rotated, the arm being preferably offset upward at 47 to permit it to be freely and conveniently grasped and being provided with a stud button or ball 48 which engages 110 a positioning socket 49 in the bar 11 in the locked position of the device as described. In locked position the lever 46 overlies the cross-bar 11. The bottom of the shaft 45 is bent laterally forming a hook 50 which is 115 controlled by the operating lever or arm 46, i. e., in the portion of the apparatus shown when the ball 48 approaches the socket 49 the hook or lateral projection 50 extends beneath the wall of the drum and also beneath the carbide holder or pocket, serving to lock and support the pocket in the drum so that it can be raised with the drum. By rotating the lever 46 to a position at right angles 120 to its present position as shown, the carbide holder may be released and it is apparent and considered an important feature of the invention by which wetting the hands and other inconveniences are avoided, the lock 125 may be operated, locking and unlocking the 130

carbide pocket from the top of the tank. This obviates the necessity for fishing the holder out of the tank after the drum is removed.

5. The apparatus also includes means for locking the drum in its position, meaning its generating or normal position relatively to the tank preventing it from floating or otherwise becoming displaced and permitting the 10 apparatus to be lifted by the cross-bar 11 which serves as a handle, the drum and cross-bar with the vent pipe 10 and the delivery pipe 9 forming a rigid structure. The means for locking the drum consists of a lever 55 preferably in the form of a ball crank having a vertical arm 56 extending down along the side of the tank from the pivot 57 by which the arm is mounted on the side of the tank near the top and a horizontal arm 58 15 preferably extending over the side of the tank, the top edge 59 of which it contacts as a stop and by which horizontal arm the lock is operated. At the bottom of the depending arm 56 is a horizontal projection or foot 67 which as seen from observation of Figure 5 swings into contact with the top of the drum at a point where it is tangent with or contacts or approaches the side wall of the tank, it being understood that the drum is round, the tank being square, at least in the 20 preferred form of the invention as illustrated and that in this position the horizontal arm of the locking lever 58 rests on the top edge of the tank. 25
35. By raising the arm 58, the foot 67 is swung to the left out of contact with the drum permitting it to be raised. In the position shown it is locked making the entire apparatus an integral unit which can be raised and moved by grasping the cross-bar 11 as a handle.

Having reference to the burner proper or burner casting 22, it will be observed that the hollowed and internally threaded boss 45. 85 which receives the swinging burner pipe 19 is at an acute angle with the burner tip 23 or more properly vice versa the axis of which burner tip is coincident with the axis of the reflector 21 so that when the pipe 19 50 is swung downward in packing or shipping position, the edge 60 of the reflector swings into full peripheral contact with the side 61 of the tank, see Figure 3, affording complete protection to the reflector. The burner is otherwise constructed with particular reference to convenience in assembling and dismounting, i. e., it is formed with a boss 63 coaxial with the burner passage 64 and adapted to receive and cooperate with the 55 collar 65 formed on the reflector support 66 to which the reflector is riveted at 67 in place of the customary screw or similar engagement. In other words, the reflector and support are centrally apertured at 68 and 69 respectively in registration to pass the

burner tip 23 and the collar 65 takes over and receives the boss 63, the parts being held in engagement in any suitable manner as by means of a set screw 70 threaded in a suitable aperture in the side of the socket 70 which permits it to contact at its end with the side of the boss.

The burner is improved and simplified in that it has clean-out means, a needle valve and a shut-off valve combined in a single member and operated simultaneously. More particularly the burner passage 64 which is threaded adjacent its outer end at 72 to receive the tip 23 has a valve seat 73 just beyond and controlling the feed passage 74 leading from the feed pipe 19 and cooperating with this valve seat 73 is a needle valve and shut-off valve 75, operated by cooperating threads 76, and the valve has a shut-off seating surface 77 and a needle 78 provided with an extension wire 79 which passes through the burner orifice 80 moving back and forth and rotating therein as the valve is opened and closed and serving to keep the aperture clear avoiding clogging of the 90 burner aperture.

The operation of the apparatus is believed to have been fully disclosed in connection with the description, it being understood that the carbide holder is filled, inserted in the drum and locked therein by rotary lever 46 to the position shown and that the drum and carbide holder are then inserted in the tank which either contains or is supplied with a requisite amount of water, the drum being in turn locked therein by the locking lever 56 which is swung out of the path of the drum as the latter is inserted, swinging the locking foot 57 out of the path of the drum by raising the arm 58 and returning 105 it to locking position by lowering the arm 58 into contact with the top edge of the tank as shown. When the apparatus is thus assembled it may be handled as an integral unit by the cross-bar 11 grasped as a handle 110 and both locks may be released from the top of the tank, the carbide holder lock by rotating the arm 46 and the drum lock by raising the arm 58. When the charge is consumed the carbide holder is removed when 115 the bottom handle becomes of great advantage in knocking loose the burned carbide which as is known to those skilled in the art, becomes caked in the holder.

The advantage of the single valve 74 serving to regulate and shut off and turn on the gas together with the clean-out wire 79, also operable with the valve are apparent in that they greatly reduce the complication and cost of the apparatus and the amount of 125 attention required to operate.

The advantage of the burner structure permitting the reflector to be removed and replaced instantaneously without removing the tip and permitting the apparatus to be 130

packed and otherwise folded for transportation in a position which not only economizes space but which protects the reflector and tip are also of great importance.

5 I have thus described my invention specifically and in detail so that the nature and operation of same may be clearly understood, however, the specific terms herein are used descriptively rather than in a limiting sense, the scope of the invention being defined in the claims.

10 What I claim and desire to secure by Letters Patent is:

15 1. In an acetylene generator, a vent pipe and locking means for holding the parts in assembled relation, the same consisting of a rod extending through the vent pipe, an arm projecting from the rod within the generator and means for rotating the rod serving to swing the arm and move it into and out of locking relation with the generator parts.

20 2. In an acetylene generator, a vent pipe and locking means for holding the parts in assembled relation, the same consisting of a rod extending through the vent pipe, an arm projecting from the rod within the generator and means for rotating the rod serving to swing the arm and move it into and out of locking relation with the generator parts and releasable means for holding said locking member in locking position.

25 3. In an acetylene generator, a delivery pipe having a swinging extension, a burner on said extension, a reflector in operative relation to the burner, the reflector being set at an angle with the extension pipe corresponding to the relation of the latter to the side of the generator whereby the reflector is caused to lie flat against the side of the generator when the extension is turned downward for convenience in packing.

40 4. In an acetylene generator, a tank, a drum, a carbide holder in the drum, an upright vent pipe, an upright delivery pipe and a bar extending across the tank near the top connecting the vent pipe and the delivery pipe the tank enclosing the drum and holder, the cross-bar fitting inside the tank and contacting it at both ends and serving as a positioning means for the drum.

45 5. In an acetylene generator, a tank, a drum, a carbide holder in the drum, an upright vent pipe, an upright delivery pipe and a bar extending across the tank near the top connecting the vent pipe and the delivery pipe, a locking member consisting of a rod extending through the vent pipe, a locking arm on the rod, and means for rotating the rod to move the arm into and out of locking relation with the holder.

60 6. In an acetylene generator, a tank, a drum having a delivery pipe and a vent pipe rigidly secured thereto and placed in upright position and a cross-bar to which

both said pipes are secured the ends of the cross-bar engaging the tank at both sides and serving to position the drum so that the said parts form a rigid integral structure.

65 7. In an acetylene generator, a tank, a drum having a delivery pipe and a vent pipe rigidly secured thereto and placed in an upright position and a cross-bar fitting snugly inside the tank and contacting the opposite sides of the tank adjacent the top of the tank to which cross-bar both said pipes are secured so that the said parts form a rigid integral structure, and means for fastening the drum in the tank.

70 8. In an acetylene generator, a square tank, a drum having a delivery pipe and a vent pipe rigidly secured thereto and placed in an upright position and a cross-bar adjacent the top of the tank extending from corner to corner of the tank to which both said pipes are secured forming a rigid integral structure the bar serving to support and position the drum and means for fastening the drum in the tank.

75 9. In an acetylene generator a drum and a tank, an upright delivery pipe, an upright vent pipe, both being rigidly secured to the drum and a cross-bar spaced above the drum and connecting the vent and delivery pipes the cross-bar extending across the tank, its ends engaging the opposite corners of the tank serving to position the drum.

80 10. In an acetylene generator, a tank, a drum having a delivery pipe and a vent pipe placed in an upright position and rigidly secured to the drum, the vent pipe extending substantially to the bottom of the drum, a carbide holder in the drum, a shaft extending down through the vent pipe, an operating arm for said shaft at the top of the tank, a hook on the shaft at the bottom of the drum, the arm serving to rotate the shaft and move the hook under the holder and to swing the hook out from under the holder engaging and releasing the holder.

85 11. In an acetylene generator, a tank, a drum having a delivery pipe and a vent pipe placed in an upright position and rigidly secured to the drum, the vent pipe extending substantially to the bottom of the drum, a carbide holder in the drum, a shaft extending down through the vent pipe, an operating arm for said shaft at the top of the tank, a hook on the shaft at the bottom of the drum, the arm serving to rotate the shaft and move the hook under the pocket and to swing the hook out from under the pocket serving to engage and release the pocket, a cross-arm near the top of the tank secured to the delivery pipe and to the vent pipe and fastening means operable from the top of the tank for locking the drum in position in the tank.

90 12. In an acetylene generator, a carbide holder consisting of uprights and pockets

having a conical bottom composed of a single piece of sheet metal, a supporting member for the holder, the sheet metal bottom having a handle or strap cut from the body of the metal and tabs also cut from the body of the metal, and means for fastening the same to the supporting member.

13. In an acetylene generator having a tank with a flat side surface, a swinging feed

pipe, a burner and a reflector secured to the end of the feed pipe, the latter being arranged with its axis at an acute angle to the pipe so that when the burner is swung down, the peripheral edge of the reflector lies flat against the side of the tank.

Signed by me at Baltimore, Maryland,
this 23rd day of February, 1922.

ALEXANDER F. JENKINS.
